United States Patent Office

Des. 232,472
Patented Aug. 20, 1974

232,472

CROCHET FABRIC

Catherine Mary Toscano, 1657½ E. Santa Clara St.,
San Jose, Calif. 95116

Filed July 27, 1972, Ser. No. 275,482

Term of patent 14 years

Int. Cl. D5—05

U.S. Cl. D47—2

The figure is a top plan view of a crochet fabric showing my new design, the other side being identical thereto.

I claim:

The ornamental design for a crochet fabric, substantially as shown and described.
